UNITED STATES PATENT OFFICE.

MARIE FÜRSTENAU, OF BERLIN, GERMANY.

STUD AND SOCKET FASTENING.

1,053,960

Specification of Letters Patent. Patented Feb. 18, 1913.

Application filed November 13, 1911. Serial No. 680,020.

To all whom it may concern:

Be it known that I, MARIE FÜRSTENAU, née BRISCH, a subject of the German Emperor, residing at Am Friedrichshain 27, Berlin, Germany, have invented certain new and useful Improvements in Stud and Socket Fastenings, of which the following is a specification.

The present invention relates to stud and 10 socket fastenings generally called press-buttons.

The press-buttons according to the present invention consists, the same as other known press buttons of this kind, of two members 15 to be sewn to either of the parts of the garment to be fastened respectively, the one of the said members having a stud, the other a socket adapted to engage over the said stud and hold the garment closed. Such 20 press-buttons are known and have been generally made of metal japanned or otherwise stained to a color to match the respective garment. Press-buttons of this kind, however, showed two disadvantages. For practical 25 reasons it was only possible to make such metal press-buttons, covered with a colored lacquer, of a few colors and in a few shades only, and it was often not possible to match them exactly to the color of 30 the material of the garment. Then such coating of lacquer would soon wear off and the bright metallic parts appear beneath it, so that the press-button afforded an unsightly appearance.

35 The object of the present invention is to obviate these disadvantages. This is obtained by providing the press-button with detachable caps, which are made of a material, which will allow of their being 40 stained, for instance by means of anilin dyes, to any color and any shade and not only on their surface but through and through. It will therefore be possible to make these 45 detachable caps of a color which will exactly match (or harmonize) with the color of a given garment, as if necessary exactly the same dyes may be employed in the manufacture of the caps and for the dyeing of the material for the garment. These caps 50 may be made of materials like celluloid, ebonite, horn, galalith or the like. It is, however, not imperative to dye the raw material of which these caps are to be made. They may also be made of a material, to 55 which a lacquer or a similar coating will

adhere well. Altogether these caps can be made in such a manner, that they will not wear so quickly as the press-buttons made of lacquered or japanned metal.

If made in a proper manner and of a suitable material these caps will show a very long life. They are readily detachable and will admit of being exchanged when necessary or may be removed, for instance, when the respective garment is to be washed, or for being used on another garment.

When the caps according to the present invention are used, it is not necessary to cover the metallic parts of the press-buttons with a lacquer or the like, as they are completely covered by the caps. The press-buttons proper may therefore be made of the naked metal and its manufacture will therefore be cheap. The cost of making the caps are very moderate and if a suitable method is employed not considerably more expensive than the covering of the metal parts with lacquer. The complete press-button with caps according to the present invention is therefore hardly any dearer than those hitherto known.

The caps may be manufactured independently in different colors and wholesale. These caps may be then sold separately and be bought according to the requirements of the respective color and shade to match the color of the garment or harmonize with it, and be then fitted on the metal parts of the press-buttons.

In the accompanying drawing several constructional forms of the press-button according to the present invention are exemplified.

Figures 1 and 2 are cross sections through a press-button according to the present invention, the several parts being still separate from each other; the caps are not clasped on to the members of the press-buttons and the members of the latter are not fastened to each other. Fig. 3 is a plan view of the same.

In the constructional form of the present invention shown in Figs. 1, 2 and 3 the stud-member 1 and the socket-member 2 have on their sides turned toward each other an annular groove 3, in which the stitching holes 5 are provided. From these holes 5 grooves 7 radiate to the edge. This edge is beveled toward the back of the member. The members 1 and 2 therefore have a comparatively

- sharp edge 9. In sewing on the members 1 and 2 the thread 11 is passed through the holes 5, along the radial grooves 7, over the edges 9 and again through the stuff 12. After the members have been sewn on, guard caps 13, 14 are fitted over the members, clearing the stud and the socket respectively. These caps may be secured to the members in any suitable manner.
- 10 In the constructional form shown in Figs. 1 and 2 these caps are elastically engaged with their flanged over edges over the beveled edges of the members 1 and 2 and thereby clasp the latter.
- 15 The material of which the caps 13, 14 are made may for instance be celluloid, ebonite, horn, galalith or some other suitable material which may be easily stained to any color. Also sheet metal may be used which is covered with a colored lacquer.
- 20 The invention shall not be limited to the constructional form here shown and described. The parts may be made of any other form and shape and be secured to each other in any other suitable manner, provid-

ing the inventive feature is maintained, namely the detachable caps are employed.

I claim:

A member of a stud and socket fastening consisting of a main part adapted to be sewed to a fabric, said part being perforated by a series of sew holes, a groove adapted to receive the sew threads on the upper surface of said part leading radially outward from each of said holes, the periphery of said part being beveled away from the upper surface, and a removable cap to cover said upper surface, together with the attaching threads, said cap having a central opening through which the stud proper is adapted to pass, and being beaded over at its edge so as to grip elastically the beveled edge of said main part.

In testimony whereof I have affixed my signature, in presence of two witnesses.

MARIE FÜRSTENAU.
